DEEP DRAFT SELF-PROPELLED STABLE PLATFORM VESSEL

Ken O. Fugate, Jacksonville, Fla., assignor, by mesne assignments, to Aerojet-General Corporation, El Monte, Calif., a corporation of California

Filed June 1, 1965, Ser. No. 85,528

Term of patent 14 years

(Cl. D71—1)

FIG. 1

FIG. 2

FIG. 3

FIG. 4

FIG. 7

FIG. 6

FIG. 5

FIG. 9

FIG. 8

FIG. 1 is a side elevation of the vessel of my invention in a horizontal attitude;

FIG. 2 is a rear elevation thereof;

FIG. 3 is a front elevation showing my new design;

FIG. 4 is a front elevation of my design showing the submarine port in the open position;

FIG. 5 is a detail view of my vessel in a horizontal attitude with the navigational bridge extended;

FIG. 6 shows my vessel in a vertical position with the submarine port in the open position;

FIG. 7 is a detail view of the aft portion of the vessel in a vertical attitude with the heliport retracted;

FIG. 8 is a detail view of the aft portion of my vessel in a vertical position but with the heliport extended; and,

FIG. 9 is a detail view showing a plan view of my vessel design with the heliport extended.

I claim:

The ornamental design for deep draft self-propelled stable platform vessel, as shown and described.
